UNITED STATES PATENT OFFICE

BERN JASSEN AND FRANK I. NUSSBAUM, OF BROOKLYN, NEW YORK

REPLACEABLE HEEL

Application filed March 12, 1932. Serial No. 598,337.

This invention relates, generally, to shoes and has particular reference to replaceable heels, or lifts therefor.

It is a generally known fact that when the lower portion of the heel or lift is but slightly worn away, a great deal of difficulty is experienced in walking, due to the comparatively restricted surface area of that portion of the heel which comes in contact with the ground. The wearer of shoes having mutilated, or worn out lifts is subjected to injury from slipping while walking, to say nothing of the unsightly appearance shoes of this nature present. Then, too, great care must be taken to replace the worn lifts, because if such replacement is untimely the permanent portion of the heel will become damaged, necessitating the removal of the entire heel.

In an effort to overcome the above and other disadvantages incidental to the usual heel lifts, our invention relates to an extremely simple and highly effective device which will permit the ready removal of the worn lift, and its replacement without the aid of any special tools, in the minimum amount of time, and requiring no particular skill in the manipulations.

A further object of the invention resides in devices of the character described which may be manufactured on a high production basis at a very reasonable cost and, either, built into the shoes, or which may be sold separately at low prices affording their general application upon shoes of the usual construction.

Other objects of this invention will herein-after be set forth, or will be apparent from the description and the drawing, in which is illustrated an embodiment of the device for carrying out our invention.

The invention, however, is not intended to be restricted to the particular construction and arrangement of parts, nor to particular applications of such construction, herein shown and described, nor to specific methods of operation, nor to various details thereof, as the same may be modified in various particulars or be applied in many varied relations without departing from the spirit and scope of the invention, a practical embodi-

ment of which has been herein illustrated and described without attempting to show all the various forms and modifications in which the invention might be embodied.

On the drawing, in which the same reference characters refer to the same parts throughout, and in which is disclosed a preferred embodiment,

Figure 1 is a view in perspective illustrating the lift in its seated position;

Figure 2 is a vertical sectional view of our invention;

Figure 3 is a bottom plan view thereof;

Figure 4 is a view in perspective of a portion of the stationary heel and illustrating the lift portion as being separated therefrom, and

Figure 5 is a detailed perspective view of the combined plate and bushing associated with our invention.

The invention, in the form or embodiment shown in the drawing and briefly described, comprises a stationary heel portion of the usual structure, a removably mounted lift, a reinforcing metallic plate associated therewith and means for securing the lift with respect to the stationary heel portion.

In the embodiment of the invention illustrated in the drawing Figs. 1 to 5, we have disclosed a lift and its securing means with respect to the stationary heel portion which may be readily applied to shoes of the ordinary structure by merely drilling a relatively small and shallow opening into the heel and pressing the assembled attachment in its proper position. In this instance the bore 55 is formed vertically into the heel portion 56, for the reception of a sleeve or bushing 57. The sleeve 57, is preferably formed integrally with a plate 58 and is further provided with a slightly enlarged and roughened portion 59, which is adapted to firmly grip the lower portion of the bore 55, thereby retaining it in its seated position. The lower portion of the heel may be formed with a depression 57' for the reception of the plate 58 as clearly shown in Fig. 2. The lift 60, is provided with an inverted T-slot 61, the widened portion of which being adapted to snugly fit the anchor plate 62. This plate,

it will be noted, is provided with an upwardly extending and angularly bent rim 63, and is adapted to conform to the contour of the inner portion of the heel 56, and its respective lift 60 for the purpose to be hereinafter described. The anchor plate 62, is also provided with an upwardly extending shaft or rod 64, which is adapted to extend through the sleeve or bushing 57. An opening is provided near the upper end of the rod 64, for the reception of a transversely extending pin 65 and is adapted to bear against the upper extremity of the coil spring 66. This coil spring, it will be noted is freely movable within the bushing 57, and its lower end adapted to rest upon the seat 67.

A pair of vertically extending slots 68 are provided in the bushing 57 and are oppositely disposed for the reception of the ends of the pin 65, for the purpose of not only guiding this pin, but for preventing its displacement with respect thereto. The lower portion of each of these slots is horizontally extended for a relatively short distance and terminates in an upwardly extended end shown as at 69, for the purpose of seating the pin 65 within its withdrawn position as shown for example in Fig. 2.

When it is desired to remove the lift 60, from its respective heel portion 56, it is merely necessary to exert a downward pull upon the lift until the pin 65 reaches the bottom of the slots when it is but necessary to turn the lift in a counter-clockwise direction at which time, the ends of the pin 65, will become seated in the ends of the slots 69. The worn lift may now be readily removed from its anchor plate 62, and a new one replaced. By a slight downward pull of the lift 60, and a rotative movement in a clockwise direction, the lift will be readily returned to its properly seated position. It may be here stated that the plate 58, is provided with a pair of downwardly extending prongs 54, for the purpose of pressing into the upper surface of the lift adjacent the slot 53, thereby effectively preventing the separation of these portions of the lift 60, and at the same time, preventing any movement thereof with respect to the heel 56. It will now be appreciated that when the lift 60, is in its properly seated position, the angularly bent rim or flange 63, will entirely obstruct the passage or opening 61, for the purpose of preventing the entering of any foreign matter within either the passageway 53, or the slit 61.

Many other changes could be effected in the particular apparatus designed, and in the methods of operation set forth, and in the specific details thereof, without substantially departing from the invention hereof which is intended to be defined in the accompanying claims, the specific description above being merely for some operative embodiments whereby the invention may be practiced.

We claim:

1. In a lift attachment for a shoe, a heel having a bore, a sleeve frictionally secured therein, a lift, a lift carrying plate having a shaft interlocked with said sleeve, and means for retaining said lift carrying plate and locking it in its unseated position to permit the ready removal and replacement of the lift, including a spring for holding it in said position.

2. In a lift attachment for a shoe, a heel having a bore, means secured within said bore for supporting a lift, and means for retaining and locking said lift in normal seated position against the heel and in disengaged unseated position with respect to said heel to permit the ready removal and replacement of the lift, including a spring for holding the lift in both positions.

3. A lift attachment for a shoe comprising a sleeve fitted within a bore in the heel thereof, a lift secured thereto by a plate, said plate having in combination a shaft extending therefrom at one portion thereof and adapted for movement within said sleeve, a lip extending from another portion of said plate adapted to engage a portion of said heel, means permitting relative movement of said shaft and sleeve but preventing displacement of these parts, and a spring interposed between said sleeve and shaft for normally retaining said lift in seated position against the heel.

4. A lift attachment for a shoe comprising a sleeve adapted to be inserted into a bore in the heel of said shoe, said sleeve having a slot therein, a lift carrying plate having a shaft mounted thereon, a pin mounted on said shaft and cooperating with said slot to limit the movement of said shaft with respect to said sleeve whereby the seated and unseated position of said lift is determined, and a spring for retaining said plate in said seated and unseated position.

In witness whereof we have hereunto signed our names.

BERN JASSEN.
FRANK I. NUSSBAUM.
